Specification of Letters Patent.

Patented Apr. 13, 1920.

Application filed May 18, 1917. Serial No. 169,449.

To all whom it may concern:

Be it known that I, CHARLES F. WILCOX, a citizen of the United States, and a resident of the city of New York, in the county of 5 Kings, and the State of New York, have invented certain new and useful Improvements in Flying-Machines, of which the following is a specification.

This invention relates to machines for 10 navigating the air, and of the class that are heavier than air and which are sustained by application of motive power while traveling in air.

The invention has for its objects: First. 15 To provide a machine which can be more perfectly controlled in flight than machines now in use. Second. To provide a machine which may be operated and employed as a mode of conveyance, with a maximum degree 20 of safety, and immunity from accident. Third. To provide a machine which may be readily propelled at variable speed, and conveniently regulated for changing the rate of speed while in flight and without reducing 25 the speed or increasing the speed of the motor or engine. Fourth. To provide a machine in which the lifting power may be readily adjusted while in flight without reducing or increasing the speed of the engine or motor. 30 Fifth. To provide a machine by which the speed of ascent or descent can be regulated and controlled while in flight without increasing or decreasing the speed of the engine or motor. Sixth. To provide guiding 35 and steering means which can be regulated and controlled while in flight and which will operate equally well when the machine is moving slowly or rapidly and whether moving in a horizontal plane or in a vertical course or in an inclined direction. Seventh. 40 To produce a machine which will be less subject to air currents and irregular conditions of the air than machines now in use. Eighth. To provide a machine which can- 45 not be capsized while in the air thereby endangering the passengers. Ninth. To pro- 50 vide a machine which may be employed for reconnaissance and observation in military operations and which may be maintained stationarily at any altitude, and any latitudinal and longitudinal point for a desired length of time. Tenth. To provide a ma- 55 chine which may be put in motion in any direction or angle of upward inclination

from a standing start as from a tower or a 55 deck of a ship.

These and further objects are attained by the new and novel means for lifting, propelling, steering and maintaining the equilibrium of the machine hereinafter described 60 and illustrated in the accompanying drawings and pointed out in my claims forming a part of this specification.

Referring to the drawings; Figure 1 is a fragmentary view, partly in section of a 65 side elevation of one form of my improved flying machine, the car and motor or engine not shown; Fig. 2, is a fragmentary plan of the steering means shown in Fig. 1. Fig. 3, is a view of the means employed as wings or 70 blades for acting upon the air and which is employed in substantially the same form for lifting and sustaining the machine and for propelling it through the air. Fig. 4, is a sectional view taken on the line *iv*—*iv* of 75 Fig. 3 showing the way in which the wings are pivotally mounted and the manner in which they may be adjusted for regulating the force they will exert upon the air when the motor is driven at a given speed. Fig. 5 80 is a detail in plan showing the under surface or the inner surface of the form of wing employed and illustrated in Figs. 3 and 4. Fig. 6 is a plan view of a modification of my machine in which two lifting or sustaining members and two propeller members and two steering members are mounted in a frame together and to which lateral wings 85 are attached, and Fig. 7, is a sectional elevation taken on the line *vii*—*vii* of Fig. 6. 90

For lifting and sustaining the machine in air, I employ a plurality of wings, as A which are mounted in a circular rim B and central bearing member C, being either curved as in Figs. 1, 6 and 7, or flat as in 95 Figs. 3, 4 and 5. The same form of wings may be used for the propelling member, or for the lifting or sustaining member of the machine, and the method employed for adjusting and regulating them is the same 100 in either manner in which they may be employed. These wings are movable in a circular direction around a central shaft, as D, or E, which is accomplished by connecting them together in wheel formation with 105 the rim B and hub or bearing member C. The lifting or sustaining member is mounted upon a vertical shaft, and the pro-

steller member is mounted on a horizontal shaft. The only difference in the lifting member and the propelling member is in size and the position of the shaft upon which they are mounted in the machine. The wings A are each pivotally mounted in the bearings, A' and A² in the rim and the hub of the wheel respectively, the said bearings being adjacent the front edge of each wing relative to the line of advance of the wings when rotating. At the rear edge of the wing is an eye A³ to admit the bearing end of a rod A⁴. Each of the wings is thus connected with a rod, and the rods are connected at their opposite end to a sleeve A⁵ by bearings A⁶. The wings are preferably arranged in a conical form as in Figs. 3 and 4 or in hemi-spherical form as in Figs. 1, 6 and 7, whereby they present a parachute form in appearance. The wings when in normal position are disposed with mating overlapping edges with close joints so that no air can pass between the wings and when the wings are in this position the motor or engine may be running at full speed so as to drive the shafts and propelling member and lifting member at a very high speed, but the machine will remain stationary. To start the machine in an upward or a horizontal direction the wings of the propelling member or the lifting member or both the propelling member and the lifting member must be turned at a slight angle of deflection so as to engage the air and exert a pressure upon it.

Reference may now be had to Fig. 4 of the drawings as an illustration of the means employed for adjusting the wings at the desired angle of deflection. The shaft D is a hollow shaft, and has slots as D' and D², to admit splines A⁷ of sleeve A⁵, and splines F' of collar F. Within the hollow shaft D is a solid shaft H which is longitudinally slidable in the hollow shaft D. The sleeve D' and the collar F are rigidly keyed to the shaft H, so that both will move relatively with the movement of the said shaft H. The object of this arrangement will be presently explained. The rim B of the wing-supporting wheel A is provided with two hub members, as C, in which the inner end of the wings are pivoted, and the hub I, in which the spokes J are seated and which serve to render the wheel rigid. The hub I is flanged as at I² and I³ (and thereby secured as against longitudinal movement relative to the bearings in which it is mounted), and mounted revolvably in bearings K' provided in the frame K of the machine. The hub I is keyed to the shaft D and rotates therewith, so that the wheel is held revolvably in the frame and is secured against longitudinal or lateral movement. A curved member K² of the

frame is provided with bearing K³ for the extreme end of the shaft D. The collar F is provided with a flange F² around which is fitted a second collar member L, with a channel L' to receive the flange F². Bearings K⁴ are provided in the frame in which are mounted the opposite ends of screw rod K⁵ having on one end a pulley K⁶ for pilot cord as K⁷, and being held against longitudinal movement by the collar members K⁸. When it is desired to deflect the wings from the normal position to exert pressure on the air when the machine is in motion or rotation, the pilot wheel (not shown) is rotated so as to rotate the screw-rod K⁵ so as to draw the collar member L from its normal position; this carries the collar, F with the connected inner shaft, and the sleeve A⁵ in the same direction, thereby drawing inwardly the connected rods A⁴ and the rear edges of the wings A whereby an opening is made between the said rear edge of each wing and the forward edge of each adjacent wing respectively. By this movement of the screw rod a most accurate adjustment of the angle of deflection of the blades is possible. To reduce the air pressure or the force of the machine on the air, the screw rod is rotated in the opposite direction and the rear edges of the wings thrown outwardly whereby the angle of deflection is relatively reduced and the machine will exert less force upon the air although still rotating at maximum speed.

In Fig. 1, the manner of mounting the lifting or sustaining member or wheel, and the propelling member or wheel, in relation to each other on a vertical and a horizontal shaft respectively, is illustrated. The arrangement for adjusting the blades or wings as described above and illustrated in Figs. 3, 4 and 5, of the drawings, is employed for adjusting the wings of the wheel on the vertical shaft and the horizontal shaft there being only one difference in the means shown in Fig. 1; i. e., two screw rods are provided instead of one being disposed oppositely of the shaft whereby the stress of retaining the wings in their position or of increasing their angle of deflection is equalized; thereby preventing any torsional strain or binding of the collar members or of the shaft. Pulleys K⁹ are provided upon the frame K for the cords K⁷. In Fig. 1 the vertical shaft E is mounted in bearings E' in the frame E², and a gear E³ is keyed thereon. In the frame E² are bearings E⁴ for the horizontal shaft D of the propeller member, and the horizontal shaft M, for the steering member N. A bevel gear D³ on the shaft D meshes with the gear E³ on the vertical shaft, and the gear M' on the shaft M meshes with said gear E³, whereby the said horizontal shafts D and M respectively, are

driven by the rotation of the vertical shaft E.

- Secured to the lower portion of the frame K is a car only a part of the upper portion being shown as O, and bearings for the vertical shaft E, are provided in said frame as at K¹⁰. In this form of the machine the shaft extends vertically upward through the middle of the car and the motor is connected 10 with the vertical shaft E, at its extreme lower end and is positioned below the car, whereby all the heavier portions of the machinery and the burden to be carried are disposed at a point below the propelling and 15 steering means and at the extreme lower portion of the machine. By this arrangement and disposition of the weight and the load to be carried, the principle of the pendulum is employed to prevent the machine from 20 overturning, and by means of the parachute shaped lifting or sustaining means which is disposed at the extreme upper end of the vertical shaft E, the principle of the parachute is employed, whereby the weight of 25 the machine and the load to be carried may be sustained and the weight at the lower end of the vertical shaft E as a pendulum will serve to maintain the machine in a vertical and upright position, so should there 30 be gusts of wind that would tend to tip or swerve the machine, the pendulous weight would instantly right the machine to its normal upright position. It will be observed that the principle of the parachute 35 and the pendulum always coöperate to maintain the machine in upright position whether the wings of the lifting member are deflected to engage the air and exert their force thereon, or in their normal position so 40 that should the motor stop the wings could be instantly brought to normal position and a parachute provided to retard descent. The wings of the lifting member and propelling means are constructed of stiff material, 45 preferably of metal, so that they will not be likely to collapse under wind-pressure, but still will have the sustaining power of a parachute at all times.
- In operation the driving shaft of the machine is continuously driven at very high speed whether it is resting in a fixed spot on the surface of the earth or poised in air, without horizontal motion or advancing through the air in a horizontal plane. 50
- As hereinbefore stated the wings take no effect on the air unless deflected from their normal position and therefore all parts of the machine may be driven at maximum speed without moving from its place. The 55 object of this arrangement is that the lifting member and the propelling member and the steering member also may be driven at a high enough rate of speed as to serve to maintain the machine in its vertical position by the power of centrifugal force as a 60 top or gyroscope and by the novel arrangement of the parts and elements of the machine. All the parts are made to subserve the object of balancing the machine and maintaining the stability and equilibrium of the device in the air. That is to say; the rotatable lifting member, serves as a gyroscope and a parachute while at the same time it carries the adjustable wings by which the lifting power is regulated and controlled; 70 and the rotatable propelling member serves as a gyroscope, and also serves to lead the machine in a forward direction and aids in steering while it propels the machine onward, and carries the adjustable wings by 80 which the speed of flight in a horizontal plane is regulated and controlled; and the rotatable steering means which will presently be more fully explained, serves the purpose of a gyroscope, and helps maintain 85 the equilibrium and stability of the machine, while at the same time it carries adjustable wings which give direction to the course of the machine in its flight through the air. The principle of the gyroscope is thus employed to maintain the stability of the machine and without adding any superfluous or unnecessary weight to the machine. It 90 will be further seen that the three rotatable members as the lifting member, the propelling member and the steering member, all rotate in planes around axes disposed at a right angle to one another, the propelling member and the steering member rotating in vertical planes at a right angle to one another and the lifting member rotating in a horizontal plane around an axis at a right angle to the axes of both the propelling 95 member and the steering member.
- Referring to Figs. 6 and 7, it may be seen 100 that two or even more of the devices as shown in Fig. 1, and above described, may be disposed in a frame in parallel relation and simultaneously operated. In the form of the machine illustrated in these figures 110 two motors as P, are mounted on the extreme lower ends of their respective vertical shafts E—E. The lower portions of the shafts are journaled in bearings K¹¹ and K¹² and clutches Q—Q are provided whereby either 115 motor may be thrown out of engagement, or so that one of the motors may be stopped and motive power provided from the other motor for driving all parts of the machine. 120
- To provide for rotating both of the vertical shafts of the corresponding lifting members by the power of one motor gears E⁵ are keyed to the said vertical shafts and meshing gears E⁶ keyed on the shaft E⁷, said shaft being journaled in bearings K¹³ 125 whereby the two shafts are caused to rotate in opposite directions, so that the lifting members will rotate in opposite directions. This opposite rotation will tend to neutralize the gyrating tendency, if any there may 130

be, of the rotating lifting members and motors and the consequent veering or swerving and twisting from the normal upright position of the machine and its departure from a straight line of advance. The propelling members are thereby also caused to rotate in opposite directions so that they also tend to maintain the equilibrium of the machine and to keep it in its normal upright position. The steering means both revolve in the same direction and rotating at a high speed serve to help maintain the machine in an upright position.

In this form of the machine the car O may be disposed between the two vertical shafts and supported in a frame O' by the bearing supports K¹¹, K¹² and K¹³. The casings of the motors P, P, are held against rotation by the brackets P' connected with the frame O' of the car. The car here shown is inclosed having glass windows, O² and doors O³. The position of passengers and engineers is indicated within the car in dotted lines. Beneath the car provision is made for carrying ballast as O⁴, and in the lower central portion of the car, is a space for supplies of fuel, food, tools, clothing, oxygen and arms as at O⁵. Steps O⁶ are provided at the rear, and wheels as O⁷ are mounted beneath the car on spring bearings as O⁸. Referring to Fig. 6, the plan of this form of the machine, corners of the car O are formed on an angle at the rear as at O⁹ and the front of the car is elliptical in form as at O¹⁰ to reduce air pressure in front and to reduce suctional force at the rear of the car when the machine is moving through the air.

It is contemplated to provide horizontally disposed wings set at a suitable angle to the horizontal longitudinal parts of the machine to facilitate planing in long and rapid flights, but I claim nothing new in the said wings of this type, except in combination with the other features and elements of my invention. The lateral wings or planes R, may be attached in any practicable manner, to the frame K of the machine, and provided with stays, R' to secure them in position. While I have not shown wings or planes of this type in Figs. 1, 2, 3, 4 of my drawings, still it is contemplated to employ them in conjunction with any type of my machine. In the several figures the direction of rotation of the wing members is indicated by arrows.

Referring to the steering means, the member N, is mounted in the frame K, (see Figs. 1 and 2 of the drawings). In the bearing M² is the rotatable shaft M, having the gear M³ keyed thereon. On the rotatable shaft M⁴ is keyed the gear M⁵, meshing with the gear M⁶. The gear M⁶ is also keyed on the shaft M⁴. The rotatable shaft M⁷ has the gear M⁸, keyed thereon and the gear M⁹ is in mesh with the gear M⁶. The gear M⁹, is

also keyed on the shaft M⁷. The shaft M¹⁰ is rotatably mounted in bearings provided in the frame, and the gear M¹¹, is keyed thereon and meshes with the gear M⁹.

By the rotation of the vertical shaft E the horizontal shaft M, is rotated by means of the gears keyed thereon, and rotation is imparted thence through the gears, M⁸, M⁶, M⁸, M⁹, and M¹¹, to the steering member N, which is keyed on the shaft M¹⁰. Surrounding the shaft M¹⁰, is a hollow shaft M¹², collared in the frame M², whereby it is held from longitudinal movement, and threaded on the hollow shaft M¹², is the collar N².

The collar N², is held against rotation by the stays, N⁶, having corresponding ends fixed to the bearings of the frame, and having their opposite corresponding ends slidably disposed through openings in the collar N².

This arrangement allows a longitudinal movement of the collar N², relative to the shaft M¹⁰, and the threaded hollow shaft M¹², when the threaded hollow shaft M¹² is rotated, since the collar slides upon the stays N⁶, disposed through the openings therethrough, when the hollow threaded shaft is rotated, while the stays N⁶ prevent the collar N² from rotating with the threaded shaft. The concentric collar N⁷, is rotatably seated in the groove N⁸, of the collar N². On the shaft M¹⁰ opposite the collar N² is slidably keyed a second collar N⁹, having the concentric collar N⁹ rigidly fixed thereon and rotatable therewith. Rods N⁵ are slidably disposed through the part N⁴ of the steering member N, said rods having corresponding ends rigidly fixed in the concentric collar N⁷ of the collar N², and having the opposite corresponding ends rigidly fixed in the concentric collar member N⁹ of the collar N². By this arrangement the concentric collars N⁷ and N⁹ are connected by the rods N⁵, and said rods being slidably disposed through openings in the part N⁴ of the steering member N, they receive the thrust imparted to the collar N² by the rotation of the hollow threaded shaft M¹² when it is rotated, while the collar N², is held against rotation by the stays N⁶, while the concentric collar N⁷, rotatably seated in the groove N⁸, rotates with the steering member N, and the collar N⁹ and concentric collar N⁷. Thus by rotation of the threaded hollow shaft M¹², the collar N², its concentric rotatable collar N⁷, and the collar N⁹ and rigidly connected concentric collar N⁹, being connected by the rods N⁵, slidably disposed through the openings in part N⁴, of the steering means, may be simultaneously shifted longitudinally of the shaft M¹⁰, while the shaft M¹⁰ and steering member N, keyed thereon are in rotation. The means whereby the threaded hollow shaft M¹² is rotated for adjustment of the said collar

135

members and connecting parts will be presently explained. The wings N^{11} are pivotally mounted in the disk wheel or steering member, and pivoted at the forward edge 5 relative to the direction of rotation, and an eye is provided at the rear edge thereof, on either side thereof, as at N^{12} . Connecting rods N^{13} connect the said wings with eyes, N^{14} of the concentric collars N^7 and N^9 respectively. By rotation of the threaded hollow shaft M^{12} the collars N^2 and N^3 with concentric collars N^7 and N^9 respectively and connecting rods, will be simultaneously moved in the same direction and the free 10 edges of the wings of the steering member be swung or deflected accordingly in that direction, so that as the steering member N rotates the wings will exert pressure upon the air and cause the steering member to 15 veer in the opposite direction carrying with it the stern of the machine and so directing the machine to the right or left as desired. This rotation of the threaded hollow shaft M^{12} is attained by means of the pulley M^{13} 20 and the pilot cord M^{14} wrapped therearound when drawn by a pilot wheel not shown.

A horizontally disposed guiding plane, for regulating the upward and downward inclination of the machine to maintain the 25 horizontal position of the horizontal shafts is provided as at R^2 and mounted on the opposite ends of the shaft M^{10} by means of bearings R^3 . I do not claim as new this 30 feature of my machine except in combination with the other features and elements of my invention. This horizontal plane member may be regulated and be controlled by any means known and common to the art and therefore details of construction of such 35 means are not shown or described herein.

Referring to the modification of my machine shown in Fig. 6 of the drawings, the steering member is shown in a slightly modified form. Two similar steering members 40 N are shown in parallel relation the upper one in the figure being shown partly in section, and therefore only this one will be described.

Referring to Fig. 6, of the drawings the 45 horizontal shaft M is mounted in bearings M^2 , of the frame K , and keyed thereon is the gear M^3 . On the rotatable shaft M^4 , is keyed the gear M^5 , the said shaft M^4 extending across the frame and having bearings 50 provided in said frame. (In the drawing which shows a duplex machine, the gear M^6 is duplicated, but in the single type of my machine, the form of steering means here shown may be used without any modification 55 except that in this form of machine the parts of the rotary steering means are duplicated, whereas in the single type of my machine, there would not be the duplication of parts). Upon the shaft M^4 , are 60 keyed the pulleys S and in bearings M^2 is

mounted the shaft M^{10} having thereon pulleys S' , said shaft being in parallel relation with the shaft M^4 , and said pulleys S and S' being wound with cables S^2 , whereby rotation is imparted from shaft M^4 to shaft M^{10} by the rotation of meshing gears M^3 and M^5 . The steering member N is rigidly keyed on the shaft M^{10} . Collared in the frame K and held against longitudinal movement are threaded rods, T , having 75 therein pulleys T' wound with cables T^2 directed around other pulleys T^3 whereby rotation is imparted to the threaded rods T . The rods T are threaded into bores in oppositely disposed portions of the collar member T^4 having a flange T^5 , seated concentrically in channel provided in collar U 80 slidably keyed upon shaft M^{10} so that by rotation of right and left threaded rods T , the collar members T^4 will move the collar members U in a longitudinal direction and 85 slidably to the right or left upon the shaft M^{10} , the collar members T^4 being held against rotation by the threaded rods T seated in the frame K , the collar members U rotate concentrically within said collar members T^4 with the shaft M^{10} . To the 90 collars U , are pivotally connected rods as N^{13} which also connect with eyes N^{14} in wings N^{11} pivotally mounted in the disk-wheel N whereby the said wings may be deflected as set forth by the rotation of the 95 threaded rods T , by drawing the cable T^2 by a pilot wheel not shown.

In Fig. 6, the two steering members and 100 the gears from which they are driven are disposed in parallel relation, the two steering members being mounted on the shaft M^{10} and the gears and pulleys on the shaft M^4 . By this arrangement both of the steering members will be caused to rotate by the 105 rotation of either one of the horizontal shafts M , geared to its respective vertical driving shaft E , so that all parts of the machine, as the lifting means and the propelling means, and the steering means can 110 be driven at all times by the power of one of the motors if one of the motors only is in operation. In Fig. 6 the horizontal guiding plane is shown disposed across the entire width of the rear portion of the machine, and is journaled upon the shaft M^{10} and may be adjusted and controlled by any suitable means in common use, but not 115 shown in the drawings. This guiding plane I do not claim as new except as a part of my machine in combination with the other 120 new and novel features and elements of my invention.

Other features and elements of my invention, including details of construction as specific means for developing power, light, automatically regulating the speed and maintaining the equilibrium, for adjusting the wings and guiding planes, for making 125 130

observations for releasing ballast, bombs, and projectiles for regulating descent and alighting after flight, for adapting my invention to starting from and alighting on water and for rendering the machine substantially invulnerable to destruction by gun-fire from below or from collision with other machines I expect to include in applications for Letters Patent, now in process 5 of preparation but not yet complete all features of which I desire to fully protect by patent and in combination with the features, elements and essential parts and details of the invention herein described, illustrated in 10 15 the accompanying drawings forming a part of this specification and pointed out in my claims hereunto annexed and forming a part hereof.

Having thus described my invention, what 20 I claim as new therein, and desire to secure by Letters Patent, is;

1. In a flying machine of the character described and having a rigid frame, a vertical shaft journaled in the frame, a winged 25 wheel rotatable with the shaft, means for adjusting the wings while rotating around the shaft so that they will exert no pressure upon the air, or any desired pressure, without varying the speed of rotation, said 30 winged wheel being disposed at the upper portion of the shaft, means whereby a car and motor are supported at the lower end portion of the shaft, a gear keyed upon the vertical shaft, a horizontal shaft, journaled 35 in the frame, said horizontal shaft having a winged wheel mounted thereon and revolvable in a vertical plane, and means for adjusting the wings of the said wheel, a gear keyed upon the horizontal shaft, at one end 40 and meshing with the gear keyed on the vertical shaft so that the horizontal shaft may be driven from the gear of the vertical shaft, and a second horizontal shaft disposed at an opposite direction from the first 45 horizontal shaft, journaled in the frame and geared to the vertical shaft; a steering wheel journaled in a yoke provided in the frame and geared to the second horizontal shaft, said steering wheel, having adjustable 50 wings mounted therein and means for reversibly deflecting the said wings, substantially as shown and described, and for the purposes set forth.

2. In a flying machine of the character 55 described having a rigid frame, a vertical shaft journaled in the frame, a parachute shaped winged and weighted wheel keyed upon its upper end, means for adjusting the wings while being rotated, a horizontal 60 shaft journaled in the forward part of the frame and geared to the vertical shaft, a wheel like the winged wheel on the vertical shaft mounted thereon, so that the second winged wheel will rotate in a vertical plane 65 at a right angle with the wheel on the ver-

tical shaft, a second horizontal shaft journaled in the frame and at a right angle with the first horizontal shaft, a weighted, winged, disk wheel, keyed upon said shaft, gearing means connecting the disk wheel 70 with the vertical shaft so that rotation will be imparted by the vertical shaft to the disk wheel, means for reversibly deflecting the wings of the disk wheel while in rotation, said disk wheel being so positioned as 75 to rotate in a vertical plane at a right angle with the plane of rotation of the wheel of the perpendicular shaft, and at a right angle with the plane of the wheel on the first horizontal shaft, whereby the centrifugal force of the several wheels will operate to prevent gyration induced by the other wheels, substantially as shown and described 80 and for the purposes set forth.

3. In a flying machine, of the character 85 described, the arrangement and combination of a plurality of wings pivotally mounted in radial relation upon two vertical shafts, and adapted to be rotated with the shafts with means for adjusting the position of 90 the wings to exert a variable pressure on the air while rotating, and a suitable frame with bearings therein whereby a right and left hand winged wheel may be mounted in parallel relation at the upper end portions 95 of two vertical shafts, and rotate therein in opposite directions, with means supported at the lower portion of the said shafts for driving the machine, and means provided for mounting two horizontal shafts in 100 parallel relation each of said horizontal shafts having thereon wheel of the character mounted upon the vertical shafts, one being a right and the other a left hand wheel, said shafts being geared to be driven 105 in opposite directions, and two parallel steering wheels each having a plurality of adjustable and reversible wings, with means for adjusting or reversing the position of 110 said wings while rotating, both of said steering wheels being driven in the same direction and gearing means for driving the said steering wheels substantially as shown and described and for the purposes set forth.

4. In a flying machine of the character 115 described, two parallel vertical shafts, journaled in the frame, a right hand winged wheel keyed to the upper end of one of the shafts, and a left hand winged wheel similar 120 to the first wheel, keyed upon the upper end of the other vertical shafts; means supported at the lower part of the frame for driving the vertical shafts in opposite directions; two horizontal shafts, mounted in the frame and geared, one to each of the vertical shafts, and each rotating in relatively 125 opposite directions, and arranged in parallel relation to one another, each of said horizontal shafts, having mounted thereon and adapted to be rotated therewith, a winged 130

wheel similar to the wheels on the perpendicular shafts, one being a right hand, and the other a left hand wheel, respectively, two winged wheels mounted upon a 5 shaft journaled in the frame, said wheels being arranged to rotate in vertical planes in alinement with the horizontal and vertical shafts with means for reversibly adjusting and for variably changing the angle of 10 deflection of the wings while in rotation, with means provided at the lower portion of the vertical shafts, for driving the said shafts with the winged wheels thereon and for carrying passengers and other weight, 15 substantially as shown and described and for the purposes set forth.

5. In a flying machine of the character described, in combination; a horizontal shaft, journaled in a rigid frame, and held 20 against the longitudinal movement in the bearings, a wheel having a central hub and a rim, said wheel having a plurality of adjustable wing members pivotally mounted therein, each wing being pivoted at its forward edge and having at its rear edge and on each side thereof, eyes, rods connected with the eyes of said wings disposed outwardly on either side of said wings, an annular collar splined upon the shaft on each 25 side of the wheel said collars having eyes for connecting the outward ends of said rods connected with the wings, and being slidable upon and rotatable with said shaft, each of said collars having an annular channel in its outer peripheral surface, a concentric collar with a flange disposed in the channel of each of the said collars, and rotatable therein, bored through the opposite portions of each of the concentric collar 30 members, threaded rods threaded through said bores and journaled in the frame of the machine, and disposed in parallel relation with the central shaft, so as to be held against longitudinal movement, pulleys 35 mounted one upon each of the threaded rods, and cables wound thereon adapted for rotating the threaded rods whereby the collar members may be moved longitudinally of the shaft, with driving means for the 40 shaft adapted to be driven by the motive power of the machine, substantially as shown and described, and for the purposes set forth.

6. In a flying machine of the character 55 described, the arrangement and combination with two vertical shafts, rotatably mounted in parallel relation in bearings in a frame, having winged wheels keyed thereon and rotatable therewith at the upper end of the 60 shafts, a motor held on the lower end of each of said shafts, and a car supported upon the shafts adjacent the motors, two horizontal shafts arranged in parallel relation rotatably mounted in bearings in the 65 frame, winged wheels rotatable thereon in a

vertical plane, driving means for the horizontal shafts geared to the vertical shafts, steering means comprising steering wheels having adjustable wings, arranged to rotate in vertical planes in alinement with the horizontal shafts and means for driving said steering wheels geared to the vertical shafts, 70 said vertical shafts each having clutch members thereon whereby the motor may be not running but the winged wheel and the upper portion of the shaft may rotate, gears on each of the shafts, a horizontal shaft rotatably mounted in bearings in the frame and having on each of its ends a gear meshing with a gear on the vertical shaft so that 75 by the operation of one of the motors, the two winged wheels can be rotated, and all parts of the machine propelled by the one motor, substantially as shown and described and for the purposes set forth.

7. In a flying machine, in combination with a rigid frame embodying a system of circular braces, connected together in intersecting planes disposed horizontally, transversely, and longitudinally of the machine; 80 a vertical shaft journaled in the frame, a horizontal shaft journaled in the frame and geared so as to be driven by the vertical shaft; propelling means comprising a substantially parachute-shaped winged wheel 85 with a plurality of adjustable wings mounted therein, adapted to serve for propelling the machine through the air in a horizontal course when mounted upon the horizontal shaft, and adapted for lifting and sustaining the machine in the air when mounted on the vertical shaft; steering means for the machine, and means for adjusting the wings of the propeller wheel on the horizontal shaft and the wheel on the vertical 90 shaft while the wheels are rotating comprising screw-threaded rods journaled in the frame, with pulleys and pilot mechanism for rotating the rods, and means for controlling the steering means, substantially as 95 shown and described and for the purposes set forth.

8. In a flying machine, in combination with a rigid frame, a plurality of vertical shafts journaled in the frame and oppositely disposed at a spaced distance from the longitudinal center of the frame; two horizontal shafts journaled in the frame and one geared to each of the vertical shafts; means supported at the lower portion of 100 the frame for rotating the vertical shafts in opposite directions and at a relatively high speed; a parachute-shaped winged wheel with wings pivoted therein at their forward edges, keyed upon each of the vertical shafts 105 and each of the horizontal shafts; means for deflecting the wings in the wheels on the vertical shafts simultaneously while in rotation, and means for deflecting the wings on the horizontal shafts simultaneously 110

115 120 125 130

while in rotation independently of the wings of the wheels on the vertical shafts, and means for steering the machine in any direction, substantially as shown and described, 5 and for the purposes set forth.

9. In a flying machine, of the character described, in combination with a rigid frame; a plurality of vertical shafts journaled in the frame at a spaced distance from 10 the longitudinal center of the frame; two horizontal shafts journaled in the forward portion of the frame and one geared to each of the vertical shafts, a winged wheel with a weighted rim and adjustable wings pivoted in the hub and rim thereof, mounted upon the upper end of each of the vertical shafts, and one on the forward end of each of the horizontal shafts; means for driving the vertical shafts in opposite directions, 15 means for driving the horizontal shafts in opposite directions; means for adjusting the wings of the wheels while in rotation, comprising screw-threaded rods adapted for moving a sleeve longitudinally of the shafts 20 for adjusting the wings while rotating at a high speed as required to produce centrifugal force for stabilizing the machine in air; with means for steering the machine substantially as shown and described and for 25 the purposes set forth.

10. In a flying machine, in combination with a rigid frame; a vertical shaft journaled in the frame, a horizontal shaft journaled in the forward portion of the frame, 30 a horizontal shaft journaled in the rear portion of the frame opposite the first horizontal shaft, a transverse horizontal shaft journaled in the frame, gearing means for driving the horizontal shafts from the vertical shaft; a parachute-shaped propeller wheel with a weighted rim and overlapping curved wings pivotally held in the wheel, and pivoted at the forward edges thereof, keyed upon the upper end of the vertical 35 shaft, and a similar wheel keyed upon the forward end of the first horizontal shaft; means for adjusting the wings of the wheels simultaneously while in rotation each wheel independently of the other; a steering wheel 40 keyed upon the transverse horizontal shaft said wheel having pivotal wings; means for reversibly adjusting the wings while in rotation; means supported at the lower portion of the frame for driving the vertical 45 shaft and the shafts geared thereto at a high speed so as to produce gyroscopic action for maintaining the machine in an upright position at all times, such gyroscopic action being supplemented by the pendulous 50 weight of the driving means and the parachute-like action of the wheel on the vertical shaft, substantially as shown and described and for the purposes set forth.

11. In a flying machine, in combination 65 with a rigid frame; a vertical shaft jour-

naled in the frame at a spaced distance each side of the longitudinal center of the frame; a horizontal shaft geared to each of the vertical shafts and journaled in the forward portion of the frame; a car supported in 70 the lower portion of the frame; a motor connected with the lower end of each of the vertical shafts whereby the shafts may be driven at a high speed in opposite directions; a winged wheel with adjustable wings 75 adapted to rotate from left to right on one of the vertical shafts, and a similar wheel adapted to rotate from right to left on the other vertical shaft; a corresponding wheel on each of the horizontal shafts said wheels 80 being adapted to rotate in opposite directions; gearing means connecting the vertical shafts; clutch means connecting the vertical shafts with the driving means of each shaft; steering means comprising winged 85 steering wheels keyed upon a transverse horizontal shaft journaled in the rear portion of the frame; gearing means connected with the vertical shafts for driving the steering wheels; means for adjusting the 90 wings of the wheels of the vertical shafts simultaneously while in rotation; means for adjusting the wings of the wheels on the horizontal shafts in the forward portion of the frame independently of the wheels on 95 the vertical shafts while in rotation; means for adjusting the wings of the steering wheels independently of the other wheels, while in rotation; spring supporting means and wheels for the car of the machine and 100 means for regulating the load of the machine, substantially as shown and described, and for the purposes set forth.

12. In a flying machine, in combination with a rigid frame; a car supported at the lower portion of the frame; vertical shafts journaled in the frame, a wheel having a central hub, radial spokes and a weighted rim, and adjustable wings pivoted at their forward edges in the wheel, keyed upon the upper end of each vertical shaft; means for driving the vertical shafts and wheels in opposite directions and at a high speed for producing gyroscopic action for stabilizing the machine; means for adjusting the pivotal wings of said wheels simultaneously 110 while in rotation; with means for propelling the car through the air, and means for steering the car in any desired direction, substantially as shown and described and for 115 the purposes set forth.

13. In a flying machine, in combination with a rigid frame a vertical shaft journaled in the frame, a horizontal shaft journaled in the frame; means for driving the vertical shaft at a high speed to develop gyroscopic action; gearing means connecting the horizontal shaft with the vertical shaft so as to drive the horizontal shaft thereby; a lifting wheel keyed upon the upper end of the 125 130

- vertical shaft; a similar wheel keyed upon the forward end of the horizontal shaft; each of said wheels comprising a central hub, a weighted rim, radial spokes supporting the rim, a plurality of curved pivotal wing members pivotally held at their forward edges in the hub and rim and in overlapping relation, rods pivotally connected with the rearward edge of the said wing-members, a sleeve slidable on the shaft within each of said wheels and being pivotally connected with the opposite ends of the said rods respectively, a collar at a spaced distance from the sleeve upon the shaft; a journal for the hub between the collar and the sleeve, a rod interior of the shaft connecting the sleeve and collar; a cross-head having a flange engaging the collar and slidable in the frame longitudinally of the shaft, threaded rods seated in threaded bores in the cross-head, pulleys on said rods, means for rotating the rods whereby the collar and sleeve may be moved longitudinally and reversibly along the shaft for adjusting the wings of each of the wheels, independently or simultaneously while in rotation; and means for steering the machine, substantially as shown and described and for the purposes set forth.
14. In a flying machine, in combination with a rigid frame; a car supporting the frame and supported thereby at the lower portion thereof, said car having wheels thereon and spring supports for said wheels; said frame comprising a plurality of substantially circular braces disposed in planes intersecting one another; a vertical driving shaft journaled in the frame; a forwardly extending shaft journaled in the frame and geared to the vertical shaft; a rearwardly extending shaft journaled in the frame and geared to the vertical shaft; a parachute-shaped wheel mounted on the upper end of the vertical shaft and adapted to be driven at a high speed so as to serve as a gyroscope rotating in a horizontal plane for stabilizing the machine and as a parachute for slackening descent, and comprising a plurality of curved adjustable wings for lifting and sustaining the machine in air; means for adjusting the wings while in rotation; a similar wheel mounted upon the forward end of the first horizontal shaft to serve as a propeller and as a gyroscope for stabilizing the machine and rotating in a vertical and transverse plane; and a steering wheel mounted on a transverse shaft in the rear of the frame and geared to the second horizontal shaft, said wheel serving as a gyroscope rotating in a vertical plane, for stabilizing the machine and for directing the course of the machine, and comprising a plurality of radial flat wings reversibly adjustable in the wheel while the wheel is rotating; means for adjusting the wings of each of said wheels independently of the other wheels while in rotation; all being arranged to obtain perfect stability of the machine in air by gyroscopic action of the wheels rotating at high speed in differential planes, the parachute-like action of the lifting wheel, and the pendulum-like effect of the car and driving means supported at the lower portion of the frame, substantially as shown and described and for the purposes set forth.
15. In a flying machine, in combination with a rigid frame; a vertical shaft journaled in the frame, a lifting wheel having a weighted solid rim keyed theron at the upper end of the shaft within the frame, a motor supported at the lower portion of the frame and a ratchet clutch connecting the motor with the shaft; a horizontal propeller shaft journaled in the forward portion of the frame and geared to the vertical shaft, a second wheel of the same construction as the first wheel, keyed upon its forward end within the frame; a horizontal shaft journaled in the rear portion of the frame and geared to the vertical shaft; a transverse horizontal shaft journaled in the rear portion of the frame and gearing means thereon driven by a gear on the second horizontal shaft; a steering wheel with a hub and a weighted rim keyed upon the transverse shaft, said wheel having a plurality of flat radially disposed reversibly adjustable wings pivotally mounted therein; and means for adjusting the wings of each of said wheels, independently of the other wheels, substantially as shown and described and for the purposes set forth.
16. In a flying machine, in combination with a rigid frame and a car supported thereby at its lower portions; a vertical shaft journaled in the frame, a lifting wheel having a central hub, a solid rim and radial spokes supporting the rim keyed on the upper end of the shaft, said wheel being substantially parachute shaped and comprising a plurality of curved wing-members, each pivotally held at its forward edge in bearings in the rim and the hub of the wheel, a rod connected with the rear edge of each wing; a sleeve slidable on the shaft and connected with said rods; a sliding collar on the shaft, means connecting the collar and said sleeve passing through the hub of said wheel; a concentric member engaging a flange on said collar and having threaded rods disposed in threaded bores therethrough; said rods being rotatably held in the frame; means for rotating the rod whereby the collar and sleeve may be moved relative to the shaft so as to adjust the wings of the wheel while the wheel is rotating at any speed; means connecting a motor with the vertical shaft for driving it at high speed, said motor being disposed at the lowermost portion of the frame so as to

act as a pendulum to coöperate with the centrifugal force of the lifting wheel, and with the parachute-like action of the wheel for stabilizing the machine and maintaining it in an upright position in air, substantially as shown and described and for the purposes set forth.

17. In a flying machine of the character described, in combination with a rigid frame; two vertical shafts journaled in the frame and at a spaced distance from the longitudinal center of the frame; a parachute-shaped wheel with adjustable overlapping wings keyed upon the upper end of each of the shafts within the frame, one being a right and the other a left hand wheel; two motors adapted to rotate in opposite directions one motor being supported at the lower end of each of the shafts below the frame, and a ratchet clutch connecting each of the motors to its respective shaft; a horizontal shaft disposed transversely between the vertical shafts above said clutches and geared to the vertical shafts; two horizontal propeller shafts journaled in the forward part of the frame; one geared to each of the vertical shafts; said horizontal shafts being rotatable in opposite directions; a wheel of the same form of construction as the wheels on the vertical shafts keyed on the forward end of each of said horizontal shafts, within the frame; two horizontal shafts journaled in the rear portion of the frame and each geared to one of the vertical shafts, a gear on the rear end of each of said shafts; a transverse shaft journaled in the frame parallel with the first transverse shaft; means for driving the second shaft from the first shaft; steering wheels each having a hub, radial spokes and a weighted rim supported by the spokes and flat radially disposed reversibly adjustable wings keyed upon the transverse shaft, said wings being hinged to the spokes at their forward edges and having rods pivotally connected with their rear edges, a collar slidable on the shaft connected with said rods upon each side of the wheels; concentric collar members revolvably engaging the collars; threaded rods journaled in the frame and threaded through the concentric collar-members and means for rotating the rods for adjusting the wings of the steering wheels simultaneously; and means for simultaneously adjusting the wings of the wheels on the vertical shafts, independently of the adjustment of the steering wheels, and means for simultaneously adjusting the wings of the wheels on the horizontal propeller shafts, independently of the other wheels, substantially as shown and described and for the purposes set forth.

18. In a flying machine, in combination with a rigid frame; a lifting wheel comprising a central hub, radial spokes and a

weighted rim supported by the spokes; a plurality of curved wing-members each having hinged bearings at its forward edge, one connected with the rim and one with the hub, said wheel being keyed upon the upper end of a vertical shaft journaled in the frame; a sleeve slidable on the shaft, rods connecting the rear edges of the wings with the sleeve, a journal for the shaft adjacent the sleeve, a collar on the shaft beyond the journal and adjacent thereto and slidable on the shaft, means connecting the sleeve and collar extending through the journal and slidably therewith longitudinally of the shaft; a concentric collar-member engaging a flange on the collar and slidable on the shaft; threaded rods seated in bores in the concentric collar member and journaled in the frame; means comprising pulleys and cables for rotating the threaded rods whereby the wings of the wheel may be adjusted while rotating; means for connecting a motor at the lowermost portion of the frame for driving the vertical shaft and wheel thereon and at a high speed for stabilizing the machine and maintaining it upright in air by the gyroscopic action of the wheel; a horizontal shaft journaled in the forward part of the frame, driven from the vertical shaft; a propeller wheel with adjustable wings mounted on the forward end of the shaft within the frame; means for adjusting the wings of the propeller wheel independently of the wings of the lifting wheel; a transverse shaft journaled in the rear portion of the frame, a steering wheel with adjustable wings and a weighted rim keyed upon the shaft; and means for manually adjusting the wings thereof independently of the wings of the lifting wheel and the propeller wheel, substantially as shown and described and for the purposes set forth.

19. In a flying machine, in combination with a rigid frame; two vertical driving shafts journaled in the upper and lower portions of the frame at a spaced distance opposite the longitudinal center of the frame; two horizontal propeller shafts journaled in the frame and each geared to one of the vertical shafts so as to be driven thereby; two horizontal steering shafts journaled in the rearward portion of the frame and geared each to one of the vertical shafts so as to be driven thereby; a transverse horizontal shaft journaled in the rear portion of the frame and geared so as to be driven from the steering shafts; a second transverse shaft journaled in the rear portion of the frame and driven from the first transverse shaft; means supported at the lower portion of the frame and adapted to drive the vertical shafts at high speed in opposite directions; lifting means mounted on the upper end of each of the vertical shafts adapted to serve as gyroscopes rotating in opposite

- directions in a horizontal plane; similar 55
wheels, one mounted upon the forward end
of each of the horizontal shafts in the for-
ward portion of the frame and adapted to
serve as propelling means and as gyroscopes
rotating in opposite directions in a trans-
verse vertical plane; steering wheels mounted
on the rear transverse shaft adapted to serve
as gyroscopes rotating in longitudinal verti-
cal planes; and means for adjusting the
lifting means, the propelling means and the
steering wheels, while the shafts are rotat-
ing, substantially as shown and described
and for the purposes set forth.
20. In a flying machine of the character
described, a rigid frame comprising substan-
tially circular braces arranged in horizontal,
transverse and longitudinal vertical planes
supporting journals for shafts and moving
parts of the machine; a vertical shaft jour-
naled in the upper, the lower and the inter-
mediate or central portion of the frame;
lifting means mounted on the upper portion
of the vertical shaft within the frame and
comprising a plurality of adjustable curved
wings arranged in overlapping relation and
pivotally held at their forward edges in a
circular rim and a central hub supported
upon the shaft; rods connecting the rear
and swinging edges of said wings with a
slidable sleeve upon the shaft between the
upper and intermediate journals; a collar
disposed slidably upon the shaft below the
intermediate journal; means extending
through the journal connecting the sleeve
and collar; means for reversibly sliding
the collar and sleeve longitudinally along
the shaft while in rotation so as to adjust
the wings of the lifting means; a car and
motor supported by the frame below the
lower journal so that the weight thereof will
serve as a pendulum to maintain the machine
in an upright position in air and coöperate
with the centrifugal force developed by the
rotating lifting means for this purpose; a
horizontal propeller shaft journaled in the
forward portion of the frame geared to the
vertical shaft, and propeller means mounted
thereon of similar construction to the lifting
means, and means for adjusting the wings of
the propeller independently of the wings of
the lifting means; a transverse shaft jour-
naled in the rear portion of the frame geared
to the vertical shaft, and a rotary steering
- wheel mounted thereon with means for regu-
lating the steering wheel independently of
the lifting means and the propelling means,
substantially as shown and described and
for the purposes set forth.
21. In a flying machine of the character 60
described, in combination with a rigid
frame embodying substantially circular
braces disposed in intersecting planes and
journals supported thereby; a vertical shaft
journaled at the upper, lower and interme-
diate portions of the frame; a horizontal
shaft journaled at the forward, the central
and intermediate portions of the frame; a
horizontal shaft journaled in the rear and
central portions of the frame, each of said 70
horizontal shafts being geared so as to be
driven by the vertical shaft; a transverse
shaft journaled in the rear portion of the
frame driven from the rear horizontal
shaft; rotary lifting means comprising a 75
plurality of adjustable curved wings ar-
ranged in overlapping relation and mounted
in wheel formation upon the upper end of
the vertical shaft; a motor supported by the
frame below the lower-most journal thereof,
and adapted for driving the lifting means
at a high speed to develope gyroscopic force
and also to serve as a pendulum to stabilize
the machine and maintain it in an upright
position in air by its weight when suspended 80
by the lifting means at the upper end of
the vertical shaft; means for adjusting the
angle of the wings of the lifting means while
in rotation; propelling means mounted
upon the forward end of the first horizontal 90
shaft and means for adjusting the propelling
means while in rotation independently of the
lifting means; rotary steering means
mounted upon the transverse shaft and
means for reversibly deflecting the steering 95
means independently of the adjusting means
of the lifting and propelling means, substan-
tially as shown and described and for the
purposes set forth.

In testimony that I claim the foregoing 100
as my invention I have hereunto signed my
name in the presence of two witnesses, this
16th day of May, A. D. 1917.

CHARLES F. WILCOX.
